UNITED STATES PATENT OFFICE.

JOSEPH BEGINS, OF LISBON CENTER, MAINE.

ATTACHMENT FOR LOOMS.

SPECIFICATION forming part of Letters Patent No. 628,914, dated July 18, 1899.

Application filed September 10, 1898. Serial No. 690,659. (No model.)

To all whom it may concern:

Be it known that I, JOSEPH BEGINS, a citizen of the United States, residing at Lisbon Center, in the county of Androscoggin and State of Maine, have invented a new and useful Attachment for Looms, of which the following is a specification.

This invention relates generally to looms, and more particularly to a construction of lug-strap attached to the picker-stick, the object being to provide an improved means whereby the lug-strap is always held against the picker-stick and kept from moving up or down and breaking off the screw and loop-strap on the picker-stick.

The invention consists also in certain details of construction and novelties of combination, all of which will be fully described hereinafter and particularly pointed out in the appended claims.

In the drawings forming part of this specification, Figure 1 is a perspective view showing a portion of the picker-stick, the loop-strap, lug-strap, and the looped bearing-strap arranged within the lug-strap and which forms the essential feature of my invention. Fig. 2 is a horizontal sectional view of all of said parts, and Fig. 3 is a detail perspective view of the lug-strap and looped bearing-strap.

In carrying out my invention I make no change whatever in the picker-stick A, lug-strap B, or loop-strap C. Within the lug-strap, however, and attached also to the pitman D, I arrange a looped bearing-strap E, which bears against the inner face of the picker-stick and holds it tight against the lug-strap, thereby preventing the lug-strap from working up and down, as heretofore, breaking off the screws and loop-strap. In practice I prefer to construct these straps of sole-leather; but it is obvious that any other suit-

able material may be used. The bearing-strap also prevents any sudden jerks upon the picker-stick, and I have found that all 45 the parts wear much better in consequence of the additional looped strap, as herein described. One end of the bearing-strap is sewed or otherwise secured to one end of the lug-strap, while the other end is slotted longitudinally, as shown at E', in order to render said strap adjustable to different sizes of picker-sticks. The same bolt F which secures the lug-strap also secures the looped bearing-strap. 50

It will thus be seen that I provide an exceedingly cheap and simple construction which will efficiently serve all the objects for which it was intended.

Having thus fully described my invention, 60 what I claim as new, and desire to secure by Letters Patent of the United States, is—

1. In an attachment for looms, the combination with the picker-stick, lug-strap, and pitman, of an adjustable slotted bearing-loop 65 arranged within the lug-strap, substantially as shown and described.

2. In attachment for looms, the combination with the pitman, of a picker-stick, a lug-strap embracing the picker-stick and secured 70 to the pitman, a bearing-strap fastened at one end to the lug-strap, and longitudinally slotted at the other end, substantially as shown and described.

3. The combination with the picker-stick, 75 loop, and lug straps, of the longitudinally-slotted looped bearing-strap constructed as described and arranged within the lug-strap and bearing against the picker-stick, substantially as shown and described.

JOSEPH BEGINS.
